UNITED STATES PATENT OFFICE.

THOMAS C. PURVES, OF LAGRANGE, ILLINOIS.

HOT-WATER HEATING SYSTEM.

SPECIFICATION forming part of Letters Patent No. 685,734, dated October 29, 1901.

Application filed January 22, 1900. Serial No. 2,296. (No model.)

To all whom it may concern:

Be it known that I, THOMAS C. PURVES, a citizen of the United States, and a resident of Lagrange, in the county of Cook and State 5 of Illinois, have invented certain new and useful Improvements in Hot-Water Heating Systems, of which the following is a full, clear, and exact description, reference being had to the accompanying drawings, and to the letters of reference marked thereon.

The object of my invention is to obtain the benefit of hot-water heat in the radiators of a steam-heating system. This I accomplish in an economical manner by making a suitable addition to the radiators without changing the construction thereof, so as to enable them to be filled with water and sealed and so that the steam of the distributing system can be utilized to heat said water, substantially as hereinafter fully described, and particularly pointed out in the claims.

In the drawings, Figure 1 is a longitudinal central section through my invention: Fig. 2 is a vertical transverse section thereof, 25 taken on dotted line α α , Fig. 1, looking in the direction indicated by the arrows.

In the drawings, A represents a three-way radiator, the sections of which are suitably connected by means of nipples a a , which 30 unite the union-chambers thereof at top and bottom. The connected union-chambers at the bottom of the radiator form what for convenience of description may be called the "main chamber" B. This chamber B extends from one end of the radiator to the other and is connected at one end by a short section of pipe b to the steam-valve C, by means of which the steam-pressure from the leader D, which communicates therewith, is controlled.

40 The preceding explanation is a brief description of a connected radiator of a modern heating system. Now my invention particularly relates to converting such a system, or one substantially like it, into a hot-water heating system, no matter whether the upper bends of the sections of the radiators are connected so as to establish a free circulation between them or not. This is effected by screwing or otherwise securing into the end 45 of the section of pipe b a blind pipe or tubular steam-chamber E, which extends to very near the opposite end of the radiator, but

preferably is not attached thereto and has said unattached end closed. The reason for not attaching both ends of the steam-chamber to the radiator is because of the unequal expansion of the two. The steam-chamber being subject to the direct action of the steam heat expands to a greater extent than the radiator, which is exposed to the action of the outer atmosphere, and would strain so at its joints with the said radiator as to either loosen the sections thereof or wrench its connections with the same in such manner as to render them leaky. Outside chamber E the space within the radiator is filled with water and the radiator is sealed. When the steam is turned into chamber E, it soon heats the water and creates a heating apparatus which provides a pleasanter and more agreeable heat than if steam were used and generates a greater heat than the present hot-water heating systems and holds its heat much longer.

When steam is turned into chamber E, the air in the same must find an escape. This could be provided for by employing a vent which would project either longitudinally or laterally from said chamber through the side or end walls of the radiator. In view of the fact, however, that the steam-chamber will expand considerably more than the surrounding walls of the radiator, as hereinbefore stated, the joints or connections of the said vent with the steam-chamber and the wall of the radiator through which it extends would become strained and leaky. I avoid this difficulty by means of a longitudinal vent-pipe e of comparatively small diameter, which extends from near the closed end of said steam-chamber into the pipe b , where the same is turned vertically and extends out through the same and has secured to its outer end an automatic vent-valve d of any suitable construction. In this way the unequal expansion of the steam-chamber and the radiator can have no effect upon the joints of the air-vent to make them either leaky or defective.

It is desirable to always keep a small quantity of steam in the chamber E to prevent the water in the radiator from freezing when valve C is closed. I therefore have provided a "by-pass," consisting of a pipe f, extending laterally from leader D, which is connected

by means of a coupling *g* to a valve-controlled pipe *h*, that is connected with the pipe *b* between the valve *C* and the steam-chamber. Thus when the valve *C* is turned off the 5 valve-controlled by-pass pipe can be opened sufficient to permit a small jet of steam to enter the steam-chamber. When the valve *C* is open, the by-pass pipe may be closed. If desired, the pipe *h* may have the valve 10 omitted, and thus allow of a small current of steam entering chamber *E* therethrough at all times. I can fill the radiators with water by setting them on end and pouring water into them through the opening into which 15 pipe *b* is screwed and then insert the chamber *E* and screw the pipe *b* home. This might prove a slow and expensive way of doing when a system having many radiators was concerned. I have therefore provided 20 for the filling of the radiators from the boiler by simply making the coupling connecting pipes *f* and *h* a T-coupling and connecting the same by means of a valve-controlled drain-pipe *k* with the bottom of the main 25 chamber of the radiator, about as shown. In this event I provide the top of one or more sections of the radiator with screw-closed openings *K*, which are opened when the radiators are being filled, so as to permit the 30 escape of the air therein. To fill the radiators, the water is forced into the entire heating system and into the radiators through the pipes *k* until said radiators are completely filled. The valve-controlled pipes *k* of the 35 radiators are then closed and the entire system drained down to the required level in the boiler. The steam is then turned on and controlled to heat the water in the radiators in the manner hereinbefore fully explained. 40 Should it be desired for any reason to empty the radiators, all that need be done is to open the valve-controlled pipes *k*.

I do not desire to be understood as limiting my improvements to either hot-water or steam 45 radiators of any particular design. So long as they possess a main chamber into which the steam-chamber can be projected they will answer the purposes of my invention; nor do I wish to be confined to the employment of 50 the steam by-pass hereinbefore described nor the drain-pipe *k*, for while its use is preferred

it is evident said pipe can be dispensed with and the radiators be filled either by placing them on end or by providing them with a water-inlet at a suitable point at the top and a 55 suitable drain at the bottom instead of filling them from the boiler hereinbefore explained. All such changes, as well as those of a mere mechanical character not involving a departure from the principle of my invention, 60 which may be broadly stated to be the heating of a water-filled radiator by an inserted steam-chamber connected with a steam-heating system.

What I claim as new is—

1. The combination with a water-filled sealed radiator of an independent steam-chamber inserted therein, one end of which extends beyond said radiator, a steam-valve connected thereto, a leader connecting with 70 said steam-valve and a valve-controlled by-pass connecting said leader and chamber.
2. The combination with a water-filled sealed radiator of an independent steam-chamber inserted therein one end of which 75 extends beyond said radiator, a steam-valve connected thereto, a leader connecting with said steam-valve, a by-pass connecting said leader and chamber, and a drain-pipe connecting said radiator with said leader.
3. The combination with a water-filled sealed radiator of an independent steam-chamber inserted therein, one end of which 80 extends beyond said radiator, a steam-valve connected thereto, a leader connecting with said steam-valve, and a valve-controlled drain-pipe connecting said radiator and leader.
4. The combination with a water-filled sealed radiator, of an independent steam-chamber inserted therein one end of which 85 extends beyond said radiator a vent-pipe extending longitudinally within said steam-chamber from near the closed end to the exterior of the outer extended end thereof, a steam-valve connected thereto, a leader connecting with said steam-valve, and a valve-controlled drain-pipe connecting said radiator and leader.

THOMAS C. PURVES.
